United States Patent Office

Des. 212,356
Patented Oct. 8, 1968

212,356

MEDICATION CART

Daniel A. Cronin, Jr., Concord, Mass., assignor to The MacBick Company, Wilmington, Mass., a corporation of Delaware

Filed Mar. 7, 1967, Ser. No. 6,102

Term of patent 14 years

(Cl. D14—3)

FIG. 1

FIG. 2

FIG. 3

FIG. 4

FIG. 5

FIG. 1 is a front side view in perspective of a medication cart embodying the design of the present invention;

FIG. 2 is a front view in elevation of the cart of FIG. 1;

FIG. 3 is a side view in elevation of the cart of FIG. 1; and

FIG. 4 is a top plan view of the cart of FIG. 1.

FIG. 5 is a rear view in elevation of the cart of FIG. 1.

The dominant features of my design reside in the portions shown in full lines.

I claim:

The ornamental design for a medication cart, substantially as shown in full line and described.
